UNITED STATES PATENT OFFICE.

CHARLES S. OAKES, OF JEANNETTE, PENNSYLVANIA.

EXPANDED-METAL MACHINE.

1,179,450.

Specification of Letters Patent. Patented Apr. 18, 1916.

Application filed March 26, 1915. Serial No. 17,243.

To all whom it may concern:

Be it known that I, CHARLES S. OAKES, residing at Jeannette, in the county of Westmoreland and State of Pennsylvania, 5 a citizen of the United States, have invented or discovered certain new and useful Improvements in Expanded-Metal Machines, of which improvements the following is a specification.

10 Expanded metal of present-day commerce is produced from ordinary sheet steel. In the course of manufacture the sheet is sheared in parallel lines of interrupted cuts; the interval between adjacent lines of cuts 15 determines the width of the strands of the finished product; the length of the individual slits which make up the lines of interrupted cuts determines the length of the meshes in the finished product; and it is the 20 staggered arrangement of the slits of succeeding rows which gives the desired reticulated form to the whole.

The sheet of expanded metal is developed in a plane oblique to that in which the 25 blank sheet originally extends. Or, stated differently, in the finished sheet the sheet metal of which the strands and bonds individually considered are formed extends in planes whose general trend is oblique to 30 the extent of the sheet of expanded metal as a whole; while the rim of each expanded slit, extends in a plane which also is oblique to the general extent of the sheet as a whole, and, approximately at right 35 angles to the general trend of the sheet material of the strands and bonds, individually considered.

My invention, generally stated, consists 40 in a die block with a surface of specific configuration: the general extent of this surface determines the general extent of the finished sheet of expanded metal, while its particular configuration is that of the particular configuration of the sheet of expanded metal in detail. In other words, 45 this die block is indeed a matrix upon which a sheet of expanded metal is cut, drawn and spread, and its configuration is, in its essential parts, exactly that which would 50 be produced in a plastic surface by pressing a sheet of expanded metal upon it.

At the beginning of the operation, the 55 blank sheet of metal extends along one edge of the die block and sustains an angular position with respect thereto; it extends indeed in a plane parallel to the small sur-

faces of the die block against which the strands and bonds of the sheet as it is developed are gradually spread.

My invention further consists of a cutter 60 and spreader which, co-operating with the die block, will properly cut, stretch and spread a plain sheet of metal placed between cutter and spreader into a sheet of expanded metal, resting against the die 65 block.

Referring to the accompanying drawings, Figure 1 shows the machine of my invention in longitudinal section, and Fig. 2 shows it in transverse section. The plane of section 70 of Fig. 1 is indicated by the dotted line I—I Fig. 2, and the plane of section of Fig. 2 by the dotted line II—II, Fig. 1. Fig. 3 is a view in front elevation of the shear member of the machine; Figs. 4 and 75 5 are views on larger scale and in perspective of fragments of die block and shear, arranged face to face in proper relative positions; Fig. 6 is a diagrammatic view, explanatory of operation; and Fig. 7 is a 80 view similar to Fig. 5, illustrating a modification in structure.

The die member 1 is shown in front elevation in Fig. 1, in vertical section in Fig. 2, and in detail and in perspective in Fig. 4. The general extent of this member, as 85 will be understood from a comparison of Figs. 1 and 2, is in a steep plane oblique to the horizontal, and it will be understood that at the beginning of the operation the blank of plain sheet metal will extend in a horizontal position along the lower edge of the die member. This initial position of the material is indicated in Fig. 2 at a—b. Of course, the terms oblique and horizontal 90 here used have merely relative significance. Manifestly, the machine as a whole may be set at any angle to the horizontal.

More minutely examined, the inclined 100 face of this die member is formed into a succession of steps (see Fig. 2) of which steps the "tread" surface determines the width of the strands of the finished product, while the "riser" determines the width of expanded mesh openings individually. Comparing Figs. 1 and 4 it will be seen that the steps are not continuous, but are interrupted by semi-hexagonal recesses—which leave semi-hexagonal blocks of like dimensions but in inverted position.

As will presently be explained, and as is apparent, considering the initial position of

the material, the displacement incident to cutting and expanding is upward; and accordingly it is the edges of these steps which constitute the cutting edges and it is the downward faces of the steps against which the slotted material is spread, stretched and shaped. Furthermore, it is the width of the base of the hexagonal recess in the step which determines the width of the bond in the finished material. Referring to Fig. 4, and selecting for consideration the central block of the group, it is the edge *c—d—e—f* against which the material is drawn and cut, and it is the lower projecting face of this block against which the slotted strand is drawn and shaped.

As Figs. 2 and 4 clearly indicate, the die blocks are built up of identical columnar hexagonal prismatic units, and these are assembled and clamped in a suitable retaining bed or frame.

It may be remarked that the over-all dimensions of the die member limit the size of the sheet of expanded metal which may be produced in a given machine; and, further, that with the arrangement indicated in Fig. 2 the overhang of the die member is the measure of the maximum width of blank which may be expanded in the machine. The shear member which co-operates with this die member to cut and spread the metal might, manifestly, travel in vertical direction; in which case, however, its traverse would come to positive stop in abutment against the stepped die member, and, furthermore, the shear would in such case have to be composite and advance section after section to effect a progressive shearing and expanding.

Instead of a shear member with a vertical traverse, I provide a shear member which moves in a direction parallel to the treads and risers of the stepped die member (that is, horizontally and longitudinally of the die member shown and described), a shear member which is stepped to correspond with and form indeed a counterpart to the stepped die member, and which moves in close proximity, across the face of the die member. The interval of separation of the treads of the stepped parts is approximately that of the thickness of the material to be worked; the risers pass one another closely, for they constitute together pairs of shears. It will be understood that in this case, as is generally true in the case of a machine of two co-operating parts, either the die member or the shear member may be made movable and its fellow stationary, or both may be movable—it being requisite only that the purposeful relative movement described is attained. But, as I have explained, I find it simple and convenient to mount the die member in stationary supports and cause the shear member to move across its face.

As shown the shear member 2 moves in a slide-way formed in the bed of the machine, being guided by the tongue and groove engagement indicated at 3, 3 and is propelled by the rack and pinion drive indicated at 4. Any suitable means of obtaining the relative movement described may of course be resorted to. As is indicated in Fig. 1, the shear member 2 may be provided with double oppositely inclined rows of cutting edges, and so adapted to operate on each reciprocation, whether in one direction or the other, instead of on every alternate reciprocation. This is a matter of preference with the builder of the machine. Figs. 1 and 3 show the two rows of cutters crossing one another; manifestly two such rows might be arranged end to end on a longer carrier.

The minute construction of the stepped shear member remains to be described. In this connection Figs. 3 and 5 are to be particularly examined and compared with Figs. 2 and 4. The shear member is characterized by a succession of cutting edges, *g—h, i—j, k—l*, etc. Each of these edges lies in a vertical plane parallel to the risers of the stepped die block, the effective edge of each extends in vertical measurement a distance corresponding to the rise of the step of the stepped die block; the edge is preferably inclined at a more gentle slope than the angular face *e—f* of the die block; there is a separate cutting edge *g—h, i—j*, etc., for each horizontal line of hexagonal blocks or each step of the die block (so that, viewed in elevation—Fig. 3—the edges of the succeeding shear members form an incline, *m—n*); and the succeeding cutting edges *g—h, i—j*, etc., are stepped in receding succession, by the steps *h—i, j—k*, etc. (cf. Figs. 2 and 5), which correspond in depth to the width of the "treads" of the stepped die block—a unit of measure which, as already explained, determines the width of strand in the finished product.

Preferably the degree of inclination of each cutting edge *g—h, i—j*, etc., is such that its horizontal extent is approximately as great as or somewhat greater than the width of each hexagonal block of the die member, so that the forward end *g* of the edge *g—h*, for example, engages a new block before the rear end *h* has passed from engagement with the next preceding block.

The operation of cutting, stretching, and shaping will be clearly understood on considering the diagrammatic showing of Fig. 6. The letter *c—d—e—f* indicate the semi-hexagonal lower outline of one of the blocks of the die member, 1, viewed in front elevation, and the letters *g—h* indicate the advancing edge of one of the cutters of the shear member 2. It will be remembered that each step of the die member is made up of a

succession of such semi-hexagonal blocks with corresponding intervals; that there is a succession of such steps, each overhanging the one beneath; and that there is one cutting edge, such as $g-h$, for each step of the die member. In this diagrammatic Fig. 6 the dotted lines indicate the material under treatment.

As the cutter advances in the direction indicated by the arrow, its forward end, co-operating with the corner e of the die block will engage and begin to cut the metal o which extends in horizontal plane and rests along one of its edges against the nether face of the block which is indicated by the edge $d-e$.

As the cutter $g-h$ advances it will raise the proximate portion of the sheet o from the level of the lower end g to the level of the upper end h , excepting only a strip which is sheared and laid up against the nether face of the block, the material so raised being brought to position where it will be engaged by the next succeeding cutting edge $i-j$, in like manner as the now severed portion o was engaged by the cutting edge $g-h$. And it will be observed that along the line $f-p$, the edge $g-h$ will not cut. That interval $f-p$ represents the length of the bond in the finished product. The next succeeding cutting edge $i-j$ will engage and cut the material across that interval, $f-p$ (though the cut will be off-set from the cut made by $g-h$), just as the edge $g-h$ has engaged and cut the material across the interval $d-e$, which was left uncut by the next preceding cutter.

If desired a clamp may be provided, securing the edge of the sheet (the edge a , Fig. 2) before the operation begins; and, furthermore, the shear-member may be provided with a guide having a lower face disposed opposite to and at an interval from the inclined upper faces of the shear-blocks, to serve as a guide for the uncut portion of the sheet while the operation is in progress. Such provisions are obvious, and are not essential to successful operation. If found desirable they may be resorted to, and manifestly my invention is not limited to ordinary engineering expedients, present or absent, as conditions of service may dictate.

In case the two rows of cutters borne by the shear member 2 are arranged to cross one another (an arrangement indicated in Figs. 1 and 3), the otherwise continuous inclines $m-n$ and $m'-n'$ formed by the upper surfaces of the shear blocks are interrupted at the crossing, as indicated at o , to allow space for the passage of the portion of the sheet which, when the cutting has advanced half way, remains to be cut by the upper portion of the apparatus. And, furthermore, while in general extent the front faces $m' o m$, $n o p$, and $n' o q$ of the

shear member (see Fig. 3) are (leaving the minute stepped formation out of account) inclined, as indicated in Fig. 2, this inclined face of the shear member is interrupted by the spaces $m' o p$, $m o q$, and $n o n'$, whose further walls (when viewed as in Fig. 3) are vertical and extend in the plane indicated by the line $r-s$, Fig. 2. This recessing of the shear member is a further provision to permit the free movement of the sheet of metal in course of treatment, (the blank of metal being assumed to be a blank of maximum size).

Such an arrangement of the operating parts as has just been described brings about a slight difference in the action of the blank under treatment. It has been said that, beginning with the engagement of the lowermost shear block with the lowermost die block, while the strips which form the meshes are being sheared, the whole of the uncut portion of the blank sheet is gradually raised, still maintaining its general horizontal extent when viewed transversely, from lower to higher level. This description is accurate in its application to the machine constructed as in Figs. 1 and 3, so far as concerns the first half of the operation; the cutting of the sheet and the attendant elevation of the uncut material is normal, as already described, from m to o (or from m' to o). But when in the progress of operation half of the blank has been cut and expanded, and the still uncut portion of the blank sheet has been raised to the level of the point o , further free rise of the uncut portion of the sheet is restrained by the now overhanging portion of the oppositely inclined line of shear members. The further cutting, from o to n (or from o to n'), is perfectly normal and is accomplished as already described. But, as cutting advances upward beyond the point o , the uncut portion of the sheet does not rise freely, but is gradually bent and drawn upward on an incline through the slot formed at o .

The individual cutters may be made as separate blocks, all alike; and for example of the identical prismatic form indicated in Fig. 5, (just as the individual die blocks of the die member are all alike, and are individually removable, replaceable, and interchangeable.) Fig. 3 shows such a series of individually distinct but identical cutter blocks secured in a common carrier and making up a single unitary shear member.

I have shown the cutters to be rigid in their carrier. In such form their operation is most clearly intelligible. But it will be understood that with such a cutting edge as $g-h$ the wear of cutting is greatest at the lower end. Therefore, in order to attain an even distribution of wear along the cutting edge, I may make the individual cutters in

the form of cylinders mounted to turn freely on bearings formed on or in the carrier. In adopting this expedient I provide cutters which present ever new portions of their edges to the repeated operation and in which wear is distributed. Such an alternative construction is indicated in Fig. 7. It needs no further description. However, I may add, that, if desired, these cylindrical cutters 10 may be rotated positively.

As shown and now described the steps of the stepped die and shear members are square cornered; it will be understood that a rectangular corner is not essential to successful operation and that modification of this angle will correspondingly modify the minute form of the product.

I claim as my invention:

1. In an expanded-metal machine the combination of a die-block and a shear-block relatively movable the one with respect to the other in a direction parallel to the plane of extent of the fed-in blank material and cooperating in such relative movement to shear stretch and shape the fed-in material, said die-block presenting mesh-shaping surfaces opposed to the advance movement of the material in the course of its fabrication and said shear block presenting a tension surface inclined to the plane of extent of the fed-in material.

2. In an expanded-metal machine the combination of a columnar die-block and a wedge-shaped shear-block arranged with the end surface of the columnar die-block and a lateral surface of the wedge-shaped shear-block opposite one another, the two said members movable one with respect to the other with their said opposite surfaces 40 adjacent one another.

3. In an expanded-metal machine, the combination of a succession of semi-columnar die-blocks arranged in line with their homologous sides in parallelism their ends 45 in a common plane and separated from one another by inverted semi-columnar recesses and a shear-block traversing the said line of die-blocks and in such traverse passing across the ends of said die-blocks, one after 50 another, said shear-block provided with an inclined forward surface.

4. In an expanded-metal machine, the combination of a die-member equipped with

a plurality of stepped rows of die-blocks and a shear-member provided with a correspondingly stepped succession of shear-blocks, the two said members movable the one with respect to the other in a direction parallel to the longitudinal extent of such steps.

5. In an expanded-metal machine, the combination of a die-member provided with a succession of rows of die-blocks and a shear-member provided with two oppositely inclined rows of shear-blocks, the two said members movable the one with respect to the other.

6. In an expanded-metal machine, the combination of a die-member whose working face is a matrix upon which a sheet of expanded metal may be formed and as such is stepped from side to side and grooved from end to end and a correspondingly stepped shear-member advancing by relative movement across the face of the said die-member from end to end, the anterior face of said shear-member (anterior with respect to the direction of such relative advance) being inclined.

7. A die-member for an expanded-metal machine including in a suitable support a plurality of identical columnar blocks arranged in a succession of stepped rows.

8. A shear member for an expanded-metal machine including in a suitable support a plurality of identical wedge-shaped blocks arranged in stepped succession.

9. A shear-member for an expanded-metal machine including in a suitable support a plurality of rotatably mounted cylindrical cutter-blocks, mounted on parallel axes, and affording a succession of stepped cutting edges and a succession of stepped inclined tension surfaces.

10. In an expanded-metal machine the combination of a matrix block shaped to conformity with one face of a finished sheet of expanded metal, and a block movable with respect thereto and in such relative movement progressively positioning, cutting and spreading thereon a blank of sheet metal engaged by and between said blocks.

In testimony whereof I have hereunto set my hand.

CHARLES S. OAKES.
